UNITED STATES PATENT OFFICE.

ARTHUR M. ROSE, OF YONKERS, NEW YORK, ASSIGNOR TO THE LOWELL
MANUFACTURING COMPANY, OF MASSACHUSETTS.

DESIGN FOR CARPET.

SPECIFICATION forming part of Design No. 26,815, dated March 23, 1897.

Application filed February 4, 1897. Serial No. 622,054. Term of patent 3½ years.

To all whom it may concern:

Be it known that I, ARTHUR MIDDLETON ROSE, a citizen of the United States, and a resident of Yonkers, county of Westchester, 5 and State of New York, have invented a new and original Design for Carpets and Borders, of which the following is a specification.

This invention comprises two parts, namely, the design A for a carpet and the design B 10 for a border, and I do hereby declare that the drawing accompanying this specification conveys to any one a clear understanding of the same and is sufficient to enable such person to use my invention.

15 The body A is characterized by festoons and vases of flower forms.

The border B is characterized by ornamental stands with vases of flower forms and festoons.

What I claim as new, and desire to secure 20 by Design Letters Patent, is—

1. In the design for a carpet, the body A, substantially as shown.
2. In the design for a carpet, the border B, substantially as shown.
3. The design for a carpet consisting of the body A, and the border B, substantially as shown.

25 In testimony whereof I have signed my name to this specification in the presence of 30 two subscribing witnesses.

ARTHUR M. ROSE.
